Patented Nov. 22, 1927.

UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

GLASS-FASTENING DEVICE.

Application filed February 11, 1926. Serial No. 87,707.

My invention relates to a device for securing a pane of glass in position in a window, and more particularly to sheet metal devices for that purpose.

5 The object of my invention is to provide an outer glass-clamping device which may be quickly and uniformly applied and which holds the glass in position with a satisfactory degree of resilient pressure.

10 The structure and minor objects of my invention will appear as the description proceeds.

In the accompanying drawings forming a part of this specification, Fig. 1 is a section across a device embodying my invention and Fig. 2 is a partial front elevation of the same, while Fig. 3 is a partial section similar to Fig. 1, but showing a different form of face plate.

20 My device is intended for clamping in position a pane 10 of glass where there is a supporting member 11 beyond the edge of the glass and having a surface substantially perpendicular to the plane of the pane, and 25 an attached supporting member or riser 12 against which the glass is adapted to rest.

A clamping member 13 is provided having a portion 14 bent towards the pane and a flange 15 on the edge of portion 14 adapted to lie against the face of the pane. The other edge of member 13 is folded back against itself on the side towards the pane to form a bead 16, and the folded portion is 30 reversely bent to form a flange 17 extending from the upper edge of the bead towards the plane of the pane and spaced away from support 11.

35 A clip 18 is provided, the upper end 19 of which rests in the groove beneath portion 14, and from this point the clip extends towards support 11 and angles away from support 12 until it is beyond the edge of the glass. At 20 the clip turns towards support 12, and has a substantially semi-cylindrical toe portion 21 resting against support 12 and a portion 22 resting against support 11 and extending away from support 12.

40 Portion 22 of the clip has an offset portion 23 adapted to lie against the side of flange 17 away from support 11, and an upwardly turned end or heel 24. Preferably, member 13 is constructed with an outwardly directed portion 25, and heel 24 is adapted

55 to rest in the angle 26 where the metal turns from portion 25 towards support 11.

Aligning holes 27 and 28 are provided in clamping member 13 and clip 18, and a screw 29 may be passed through these holes into support 12 and draw the clamping 60 member against the pane.

It will be readily seen that, in the assembled device, the clip holds out the lower edge of member 13, so that bead 16 lies against support 11 evenly in a straight line 65 and similarly flange 15 presses evenly against the glass. The clip allows limited yielding to pressure, in order to avoid undue pressure upon the glass, and at the same time prevents such distortion of the clamping member as would result in pressure on the glass only at points close to the securing screws.

70 Clips shaped as shown may be placed in position within the clamping member before the member is positioned against the glass, and the grooves in which the two ends of the clip rest prevent its dropping out of place. The aligned openings 27 and 28 insure that the securing screws will be positioned at a predetermined angle and will 75 exert pressure in a uniform direction.

75 In Fig. 3 there is shown a modified form of outer clamping member or face plate 13a. Parts in Fig. 3 are designated by the same reference numerals as corresponding parts in Fig. 1 with the letter "a" added. It is clear that, while the face plates shown in Figs. 1 and 3 differ in shape and appearance, they operate in the same way, 80 there being no difference in the essential features, so far as this invention is concerned.

85 It is obvious that various other changes may be made in the exact structure of the parts and their several portions within the scope of the appended claims which define my invention.

90 What I claim is:

1. In a window pane support, an inner 100 member against which a pane may rest and extending beyond the edge of the pane, an outer clamping member having one edge adapted to rest against the pane and the other edge extending beyond the pane, there being a groove along the inside of each edge of said outer clamping member, and a clip 105 having its ends in said grooves, one end of

the clip being offset to form a shoulder against which the adjacent edge of said outer clamping member engages, said clip having an intermediate portion extending 5 past the edge of the pane and presenting a rounded surface adapted to engage said inner member.

2. In a window pane support, an inner member against which a pane may rest and 10 extending beyond the edge of the pane, an outer clamping member having one edge adapted to rest against the pane and the other edge extending beyond the pane, there being a groove along the inside of each edge 15 of said outer clamping member, and a clip having its ends in said grooves and having an intermediate portion extending past the edge of the pane and presenting a rounded surface to said inner member, the edge of 20 said clip which is beyond the pane being offset to form a shoulder against which the adjacent edge of the outer clamping member engages, and a screw passing through said outer member and clip into said inner member, said screw being located between the rounded surface and the portion of the 25 clamping member which engages the pane.

3. In a window pane support, a supporting member beyond an edge of the pane and 30 having a surface substantially perpendicular to the plane of the pane, an inner supporting member having a surface substantially parallel with the pane and against a portion of which the pane is adapted to rest, an outer clamping member having one edge adapted 35 to rest against the pane and the other edge adapted to rest against the first said support and a clip having an end engaging the second said edge of the outer clamping member and extending thence along the first said surface, against the second said surface and then bending back to the outer clamping member.

4. In a window pane support, a supporting 45 device having a surface against which one face of the pane rests and another surface beyond the edge of the pane and substantially perpendicular thereto, an outer clamping member having one edge adapted to rest 50 against the pane and the other edge adapted to rest against the second said surface, said clamping member being provided with a flange adjacent the second said edge, extending 55 towards the first said surface and spaced away from the second said surface, a clip having one end resting against the flange, an intermediate portion extending to and 60 against the first said surface, and its other end extending to the outer clamping member adjacent its glass-engaging edge, and

means for drawing said outer clamping member towards the first said surface.

5. In a window pane support, an inner clamping member, a sheet metal outer clamping member having one edge adapted to rest 65 against the glass, a clip having one end engaging said edge of the clamping device, having a portion extending from said end to a point midway between the inner and outer clamping members, and a portion extending 70 from the first said portion to and against the inner clamping member and then to the other edge of the outer clamping member, and a screw passing through the outer clamping member and the first said portion of the 75 clip into the inner clamping member.

6. In a glass fastening device, a sheet metal clamping member having a groove adjacent each edge, a clip having its ends resting in said grooves and having a central U-shaped portion extending away from the clamping member, and supporting means having a surface against which the glass bears and a surface perpendicular thereto, said U-shaped portion of the clip normally 85 bearing against both of said surfaces, the end portion of the clip remote from the glass being offset to form a shoulder against which the adjacent edge of the clamping member engages. 90

7. In a glass fastening device, the combination with a frame, of a sheet metal clamping member having a groove adjacent each edge, a clip having its upper end in one of said grooves and having a rounded nose 95 bearing against the frame, the lower end portion of said clip extending into the other groove and being offset to form a shoulder against which the adjacent edge of the clamping member engages, said offset portion terminating in a heel which extends obliquely across the groove to the inside edge thereof, and a screw between the nose and the upper end of the clip for securing the 100 clamping member to the frame. 105

8. In a glass fastening device, a sheet metal clamping member having a groove adjacent each edge and a clip having its ends resting in said grooves and having a central U-shaped portion extending away 110 from the clamping member, one end of the clip being offset to form a shoulder against which the adjacent edge of the clamping member engages, said member and clip having openings alining in a direction substantially parallel with that in which said U-shaped portion extends. 115

In testimony whereof, I have hereunto subscribed my name to this specification.

CHARLES G. NELSON.
